6 Claims. (Cl. 260—294)

The present invention relates to piperidine derivatives having favorable physiological properties which may be used as antitussive agents, and to a process for the manufacture of these substances. The invention likewise relates to pharmaceutical preparations showing antitussive efficiency and containing the piperidine derivatives as active ingredients.

We have found a process for the manufacture of piperidine derivatives of the general Formula I:

in which R stands for a hydrocarbon radical having up to 10 carbon atoms and containing one or more double linkages which may be substituted by halogen, amino, or alkyl or alkoxy having up to 3 carbon atoms, R₁ stands for alkyl having up to 4 carbon atoms, and R₂ stands for hydroxy or alkoxy having up to 4 carbon atoms, wherein an amine of the general Formula II:

in which R₁ and R₂ have the meanings given above, is reacted with a carboxylic acid of the general formula R—COOH, in which R has the meaning given above, or a halide, an anhydride, an ester or an azide of said acid, the compounds of the general Formula I being converted into their addition salts with physiologically tolerable acids where such salts are required.

As reactive derivatives of carboxylic acids, the corresponding halides, preferably chlorides and bromides are used, furthermore, for instance, anhydrides, esters or azides. The carboxylic acids referred to may contain one or several double linkages in the molecule. These double linkages may likewise be present in an aromatic ring system. The following carboxylic acids may be used, for instance: dimethyl-acrylic acid, crotonic acid, α -methyl-crotonic acid, α, β -dimethyl-crotonic acid, β -chloro-iso-crotonic acid, β -ethyl-crotonic acid, α -ethyl- β -methyl-crotonic acid, sorbic acid, cinnamic acid, benzoic acid and their derivatives, such as salicylic acid, acetyl-salicylic acid, benzoic acids substituted by halogen, amino or alkyl or alkoxy having up to 3 carbon atoms, as well as their di- and tetrahydro-derivatives, naphthoic acids, diphenyl-carboxylic acids; the use of α, β -unsaturated carboxylic acids having 4 to 5 carbon atoms, e.g. dimethyl-acrylic acid and benzoic acid, being of particular advantage.

2

The above-mentioned carboxylic acids are reacted with the following amines, for instance:

5 1-methyl-4-aminomethyl-4-(o-, m- or p-methoxy-phenyl)-piperidine, 1-methyl-4-aminomethyl-4-(o-, m- or p-ethoxy-phenyl)-piperidine, 1-methyl-4-aminomethyl-4-(o-, m- or propoxy- or isopropoxy-phenyl)-piperidine, 1-methyl-4-aminomethyl-4-(o-, m- or p-n-butoxy-, sec.butoxy- or iso-butyl-phenyl)-piperidine; instead of 1-methyl, there may also stand 1-ethyl, 1-n-propyl, 1-isopropyl, 1-n-butyl, 1-sec.butyl or 1-isobutyl. It is of advantage to use 1-methyl-4-aminomethyl-4-(m-methoxy-phenyl)-piperidine.

10 The process of the invention is materialized by acylating one of the above-mentioned amines with one of the above-mentioned carboxylic acids or its reactive derivatives. Carboxylic acid halides, especially chlorides or bromides are favorably used as starting substances. Acid halides are reacted with the amines at a temperature between 0 and 120° C., preferably between 0 and 30° C. Acid azides are reacted at 0–30° C., whereas free acids and acid esters are reacted between 60 and 200° C., the esters preferably at a temperature between 150 and 200° C.

15 The reaction may be carried out with or without the use of solvents. As solvents there are suitable, for instance, diethyl ether, diisopropyl ether, dibutyl ether, tetrahydrofuran and dioxane. Furthermore, ketones, such as acetone, methyl-ethyl-ketone, hydrocarbons such as petroleum ether, benzene, toluene, xylene, furthermore dimethyl-formamide, ethyl acetate or acetonitrile can be used as solvents.

20 In the course of the reaction of the acid halides with the amines the hydrogen halide is liberated and bound by the tertiary amino group in the reaction mixture. If a solvent is used in which the salt thus formed is insoluble or sparingly soluble, the reaction product is in many cases obtained as crystallized hydro-halide of the corresponding basic amide. If necessary, the products may be purified according to the usual methods, for instance by recrystallizing or converting them into the free base and subsequent addition of an appropriate acid.

25 For binding the hydrogen halide, another amine may be used, especially a tertiary amine such as trimethylamine, triethylamine, dimethylaniline or pyridine, which, if desired, simultaneously serves as a solvent. Furthermore, an excessive amount of the starting amine or an alkali metal hydroxide, an alkali metal carbonate, an alkaline earth metal hydroxide or an alkaline earth metal carbonate may be used as a hydrogen halide binding agent. Finally, it is possible to carry out the reaction in an aqueous suspension in the presence of alkaline or alkaline earth agents. In this case, the reaction products are formed as free bases which, if desired, are converted into the corresponding salts by treatment with physiologically tolerable organic or inorganic acids.

30 The products of the invention are valuable medicaments. They are well tolerated and show favorable pharmacological properties. They are especially suitable as antitussive agents. Some of them likewise show a sedative efficiency.

35 45 50 55 60 65 70 From German Patent 1,112,514 basic carboxylic acid amides are known which are open-chain compounds analogous to those obtained according to the process of the present invention. It is surprising that the physiological action of the novel compounds differs from that of the known substances. Whereas, for instance, the known β -methyl-crotonic acid-2-(m-methoxy-phenyl)-2-(β -dimethylamino-ethyl)-butylamide-hydrochloride (A) shows a strong analgesic and, practically, no antitussive efficiency, the compounds prepared according to the process of the present invention, for instance 4-(β -methyl-crotonoyl) - aminomethyl - 4-(m-methoxy-phenyl)-1-methyl-pi-

peridine-hydrochloride (B), and 4-benzoyl-aminomethyl-4-(m-methoxy-phenyl)-1-methyl-piperidine-hydrochloride

(C)

practically show no analgesic but a strong antitussive efficiency.

The Tables I and II show these effects and, in comparison therewith, the known effects of codein which simultaneously is a strong analgesic and antitussive agent.

(I) *Test regarding analgesic efficiency in mice (according to Wolf, Hardy and Goodell [J. Clin. Invest. 19, (1940), 659])*

Compound	Dose in mg./kg. s.c.	Analgesic efficiency
Codein.....	20	Strong effect.
A.....	20	Do.
B.....	50	No effect.
C.....	50	Do.

(II) *Test regarding antitussive efficiency in cats (according to R. Domenjoz [Naunyn-Schmeidebergs Arch. Exp. Pathol. Pharmakol. 215 (1952), 18])*

Compound	Dose in mg./kg. i.v.	Antitussive efficiency
A.....	2	No effect.
B.....	0.7	Equally strong effect.
C.....	0.7	
Codein.....	1.0	

According to the above pharmacological test results, a dose of 0.7 mg./kg. of the products of the invention provokes the same antitussive effect as a dose of 1 mg./kg. of codein. In contradistinction to compounds of similar structure, and to codein, they show no analgesic effect when given in the above-mentioned doses. The absence of analgesic efficiency means an advantage for antitussive agents, particularly since the use of substances like codein which show analgesic as well as antitussive activity implies the risk of addiction.

The products of the present invention are used as such or in the form of their salts. For salt formation, for instance, hydrohalic acids such as hydrochloric or hydrobromic acid, sulfuric acid, phosphoric acid, amidosulfonic acid and organic acids such as formic acid, acetic acid, malonic acid, succinic acid, lactic acid, maleic acid, p-amino-salicylic acid and aceturic acid can be used.

The compounds are processed into pharmaceutical preparations by mixing them with physiologically tolerable, usual organic or inorganic, solid or liquid carriers which do not react with the compounds, for instance,

water, gelatin, lactose, starch, magnesium stearate, talc, vegetable oils, benzyl alcohol, gum, polyalkylene-glycols, cholesterol. They are used, for example, with or without addition of wetting agents, emulsifiers or stabilizers, as solutions or suspensions, tablets, dragees, in capsules or in the form of suppositories.

As single dose 5 to 50 milligrams are used.

The following examples serve to illustrate the invention but they are not intended to limit it thereto:

10

EXAMPLE 1

4-benzoyl-aminomethyl-4-(m-methoxy-phenyl)-1-methyl-piperidine-hydrochloride

15

(a) To a solution of 14 grams of benzoyl-chloride in 300 cc. of benzene, a solution of 23.4 grams of 1-methyl-4-aminomethyl-4-(m-methoxy-phenyl) - piperidine (boiling point of 144-146° C. under a pressure of 0.1 mm. of mercury) in 100 milliliters of benzene is gradually added while stirring at 20-30° C. Stirring is continued for 30 minutes. The crystalline magma thus formed is filtered with suction, dried and recrystallized from methanol by adding ether. 30.2 grams of 4-benzoyl-aminomethyl-4-(m-methoxy-phenyl)-1-methyl - piperidine hydrochloride are obtained which, after drying at 80° C. under a pressure of 20 mm. Hg, melt at 194-196° C.

20

(b) The same compound is obtained, if instead of benzoyl chloride the equivalent amount of benzoic acid anhydride is used and the reaction mixture is heated to the boil for 1 hour. For the conversion into the hydrochloride, the reaction mixture is triturated with dilute sodium hydroxide solution and the benzene layer is neutralized by means of hydrogen chloride after drying by

25

means of anhydrous potassium carbonate.

(c) The same compound is obtained by heating 25 grams of benzoic acid methyl ester, 23.4 grams of 1-methyl-4-aminomethyl-4 - (m-methoxy-phenyl) - piperidine and 0.2 gram of sodium methylate in an atmosphere of nitrogen for 6 hours to 180-200° C. The reaction mixture is taken up in hot isopropanol, acidified with isopropanolic hydrochloric acid and after filtration a seed crystal is added. After several recrystallizations, 3.6 grams of the compound melting at 194-196° C. are obtained.

30

(d) The same compound is obtained by adding a solution of 5.5 grams of 1-methyl-4-aminomethyl-4-(m-methoxy-phenyl)-piperidine in 75 cc. of ether to a solution of 3.7 grams of benzazide in 50 cc. of ether, while cooling with ice, and allowing the mixture to stand for some days excluding moisture. The reaction mixture is then triturated several times with dilute sodium carbonate solution. The ether solution is dried with sodium sulfate and acidified by means of methanolic hydrochloric acid, and the salt thus obtained is recrystallized from isopropanol. 1.8 grams of the hydrochloride melting at 194-196° C. are obtained.

35

(e) The same compound is obtained by suspending 23.4 grams of 1-methyl-4-aminomethyl-4-(m-methoxy-phenyl)-piperidine in 200 cc. of normal sodium hydroxide solution while vigorously stirring, and by gradually adding 15 grams of benzoyl chloride while cooling with ice. The reaction product is taken up in ether and converted as described above into the hydrochloride melting at 194-196° C.

EXAMPLE 2

4-(β-methyl-crotonoyl)-aminomethyl-4-(m-methoxy-phenyl)-1-methyl-piperidine-hydrochloride

70

11.9 grams of β-methyl-crotonic acid chloride and 23.4 grams of 1 - methyl - 4 - aminomethyl - 4-(m-methoxy-phenyl)-piperidine are reacted according to the method described in Example 1(a). 29.5 grams of 4-(β-methyl-crotonoyl) - aminmoethyl - 4 - (m-methoxy-phenyl) - 1 -

methyl-piperidine-hydrochloride are obtained, melting at 149-152° C. after recrystallization from acetone.

EXAMPLE 3

4-benzoyl-aminomethyl-4-(m-hydroxy-phenyl)-1-methyl-piperidine-hydrochloride

8.3 grams of 1-methyl-4-aminomethyl-4-(m-hydroxy-phenyl)-piperidine-dihydrobromide (prepared from 1-methyl - 4 - aminomethyl-4-(m-methoxy-phenyl)-piperidine by reaction with hydrobromic acid of 63% strength at 120° C.) are dissolved in 180 cc. of absolute ethanol; 20.2 cc. of 2.15 N-methanolic sodium-methylate solution are added and the solution is concentrated by evaporation. The free base thus obtained is taken up in benzene, separated from sodium bromide and reacted with 3 grams of benzoyl-chloride. The reaction mixture is stirred for 1 hour at 40 to 60° C. 7 grams of 4-benzoyl-aminomethyl-4-(m-hydroxy-phenyl)-1-methyl-piperidine - hydrochloride are obtained melting at 257 to 260° C. after having been recrystallized from a mixture of methanol and ether.

EXAMPLE 4

4-(p-ethoxy-benzoyl)-aminomethyl-4-(m-methoxy-phenyl)-1-methyl-piperidine-hydrochloride

To a solution of 23.4 grams of 1-methyl-4-aminomethyl-4-(m-methoxy-phenyl)-piperidine in 300 cc. of benzene heated to the boil, a solution of 18.5 grams of p-ethoxy-benzoyl-chloride in 100 cc. of benzene is gradually added while stirring. After cooling, the reaction product is filtered with suction, washed with ether and recrystallized from ethanol. 15.8 grams of 4-(p-ethoxy-benzoyl)-aminomethyl-4 - (m-methoxy-phenyl) - 1-methyl-piperidine-hydrochloride melting at 237-239° C. are obtained.

EXAMPLE 5

4-(2'-chloro-6'-methyl-benzoyl)-aminomethyl-4-(m-methoxy-phenyl)-1-methyl-piperidine

To a solution of 18.9 grams of 2-chloro-6-methyl-benzoyl-chloride in 300 cc. of ether, 23.4 grams of 1-methyl-4-aminomethyl-4-(m-methoxy - phenyl) - piperidine are dropwise added while stirring, the temperature being allowed to reach the boiling point of the solvent. The reaction product is isolated in usual manner. 34.5 grams of 4-(2'-chloro-6'-methyl-benzoyl)-aminomethyl-4-(m-methoxy-phenyl)-1-methyl-piperidine are obtained, showing a melting point of 152-154° C. (from a mixture of methanol and ether).

We claim:

1. A compound of the formula

in which R is selected from the group consisting of a hydrocarbon radical, halo-hydrocarbon, aminohydrocarbon, alkyl and alkoxy hydrocarbon radicals wherein the hydrocarbon portion has at least one double linkage and up to ten carbon atoms and the alkyl and alkoxy portions have up to three carbon atoms, R₁ stands for alkyl having up to four carbon atoms, and R₂ stands for hydroxy or alkoxy having up to four carbon atoms, and addition salts thereof with a physiologically tolerable acid.

2. 4-benzoylaminomethyl - 4 - (m-methoxyphenyl)-1-methyl-piperidine.

25 3. 4-(β-methyl-crotonylamino-methyl) - 4 - (m-methoxyphenyl)-1-methyl-piperidine.

4. 4-benzoylaminomethyl-4 - (m-hydroxyphenyl) - 1-methyl-piperidine.

30 5. 4-(p-ethoxybenzoylaminomethyl) - 4 - (m-methoxyphenyl)-1-methyl-piperidine.

6. 4 - (2' - chloro-6'-methyl-benzoylaminomethyl)-4-(m-methoxyphenyl-1-methyl-piperidine.
